UNITED STATES PATENT OFFICE.

WILLIAM E. STRATTON, OF VOLTAGE, OREGON.

TOOL-HANDLE.

1,211,783.

Specification of Letters Patent.

Patented Jan. 9, 1917.

Application filed November 23, 1915. Serial No. 63,058.

To all whom it may concern:

Be it known that I, WILLIAM E. STRATTON, a citizen of the United States, residing at Voltage, in the county of Harney and State 5 of Oregon, have invented certain new and useful Improvements in Tool-Handles, of which the following is a specification.

My invention relates to tool handles and more particularly to an extension handle 10 preferably, though not necessarily associated with a pipe wrench.

The primary object of my invention resides in the provision of a slidable telescopic section for association with a stationary section as well as the novel means 15 on both of the sections for permitting the relative adjustment of the sections.

Another object of my invention resides in the provision of a novel means carried by 20 one of the sections for removably holding the other of the sections in association therewith and preventing accidental displacement thereof.

A still further object of my invention resides in the provision of a device of the character described that is simple in construction, efficient in operation and one that can be manufactured and placed on the market at a minimum cost.

Other objects as well as the nature, characteristic features and scope of my invention 30 will be more readily understood from the following description taken in connection with the accompanying drawings and pointed out in the claims forming a part of this specification.

In the drawings:—Figure 1 is an elevational view of my invention, the sleeve section being shown in section to illustrate the 40 construction thereof; Fig. 2 is a side elevational view of the handle sections; and Fig. 3 is a transverse sectional view taken on the line 3—3 of Fig. 2 and in the direction in which the arrow points.

Referring more particularly to the drawings in which similar reference numerals 45 designate like or corresponding parts throughout the different views, I provide a shank 1 threaded adjacent its outer end as illustrated by the numeral 2, the outer terminal of the shank provided with a rigid jaw 3, the threaded portion of the shank being engageable with a sliding jaw 4 operable

through the medium of a knurled nut 5 on the threaded portion. It is to be understood 55 that this construction above described forms no essential part of my invention being merely shown and described to illustrate some of the advantages of my invention.

The free end of the shank 1 constitutes 60 one section of my improved handle and it is provided with a plurality of threads 6 for facilitating the maintenance of the sleeve section 7 thereabout and in various adjusted positions thereon. The sleeve section 7 is 65 preferably oval shaped in cross section and the inner surfaces of the long sides adjacent the end thereof are provided with projections 8. These projections 8 are provided with arcuate grooves 9 of a configuration 70 slightly larger than the thread 6 so that when the sleeved section is associated with the threaded section in such a manner that the projections 8 register with the flattened sides 10 of the threaded section 6, the sleeve 75 section can be slid into its desired position of adjustment with respect to the threaded section whereupon the sleeved section 7 can be partially rotated so that the threads 6 will enter the grooves 9 and maintain the 80 two sections in removable adjusted position.

In order to prevent the accidental displacement of the sleeved section from the threaded section, I have provided an oval shaped plug 11, the latter having a longitudinal opening 12 therein in which is inserted an elongated screw bolt 13, the inner threaded terminal of which is removably engaged in a correspondingly threaded, inwardly extending recess 14 in the outer end 90 of the threaded section. As is apparent from the connection shown in the drawings, partial rotation of the plug with respect to the threaded section is permitted during the adjustment and partial rotation of the 95 sleeved section. Likewise the screw bolt can be tightened after adjustment to prevent accidental disengagement of the parts, as will be readily appreciated.

Although I have shown and described the 100 preferred embodiment of my invention, I desire to be understood that I am not to be limited to the exact details shown, however, I desire that great stress be laid upon the peculiar and novel means for facilitating 105 the sliding adjustment of the sleeved section

with respect to the exteriorly threaded section as well as the novel means for preventing accidental displacement of one section from the other.

5 In practice the invention is particularly useful when a pipe wrench is being used and where a few more inches of leverage is required to adjust the work properly. It will be understood that by operating the 10 sleeve section to the outer end of the threaded section, the handle would be long enough to allow the obtaining of a proper adjustment without encountering the old inconvenience of attaching a pipe to the handle 15 of a pipe wrench.

From the above description taken in connection with the accompanying drawings, it can easily be seen that I have provided a device that is simple in construction, containing but a few simple parts that can be 20 cheaply manufactured and assembled and when assembled can be placed upon the market and sold at a minimum cost.

Having thus fully described my invention, what I claim as new and desire to secure by Letters Patent, is:—

1. A handle for tools including a pair of sections, one of which is solid and screw threaded having the opposite sides thereof 30 flattened while the other is hollow and oval shaped in cross section to telescope the solid section, partially threaded projections arranged on opposite sides of the inner bore of the hollow section for removably and adjustably engaging the solid section, a plug 35 corresponding to the contour of the hollow section, and a threaded bolt passing through the plug and engaging the adjacent end of the solid section to prevent accidental dis- 40 placement of the sections and adapted to be tightened to cause the plug to frictionally

engage the end of the solid section to positively prevent accidental disengagement of the sections from each other subsequent to adjustment.

45

2. A handle for tools including an exteriorly threaded section flattened at diametrically opposite sides, an oval shaped sleeved section for telescoping the threaded section, oppositely arranged projections integral 50 with and extending from the inner sides of the sleeved section adjacent one end thereof, the front faces of the projections being flattened and arranged in uniformly spaced parallel relation with each other and provided with a plurality of uniformly spaced grooves which constitute in effect partially threaded portions, the flattened sides of the threaded section being arranged in close relation with the flattened faces of the projections 60 and slidable therebetween, the threaded section being rotatable so that the threads will engage the partially threaded portions of the projections, consequently holding the sections in various adjusted positions, an 65 oval shaped plug, and a bolt passing through the plug and engaging the adjacent end of the exteriorly threaded section for normally permitting of the partial rotary movement so that the sections may be adjusted and for 70 preventing disengagement of the sections one for the other and also adapted to be tightened to cause the plug to frictionally engage with the threaded section to prevent accidental disengagement of the sections, subsequent to adjustment.

In testimony whereof I affix my signature in presence of two witnesses.

WILLIAM E. STRATTON.
